UNITED STATES PATENT OFFICE.

EDGAR ROUSE SUTCLIFFE, OF LEIGH, ENGLAND.

TUNNEL-KILN.

1,042,725.

Specification of Letters Patent.

Patented Oct. 29, 1912.

Application filed June 15, 1911. Serial No. 633,245.

To all whom it may concern:

Be it known that I, EDGAR ROUSE SUTCLIFFE, a subject of the King of Great Britain, residing at Leigh, England, have 5 invented certain new and useful Improvements in Tunnel-Kilns, of which the following is a specification.

This invention relates to improvements in the construction of tunnel kilns in which 10 the goods are fired while passing along the tunnel on trucks; and the objects of the improvements are, first, to provide for the thorough and rapid combustion of the gases at the firing zone, so that quicker and more 15 economical working can be secured; second, to better distribute the gases so that they are completely burned before coming in contact with the briquets. I attain these objects by the construction illustrated in the 20 accompanying drawing, in which:—

Figure 1 is a vertical section of the entire kiln; Fig. 2 is a plan view, with the left hand part shown as a section on the line *x, y*, of Fig. 1; and Fig. 3 is a section 25 through the combustion chamber on the line *a, b*.

Referring to the drawings, A represents the preliminary heating zone, B the heating zone proper, C the combustion chamber, D 30 the air heating zone, and E the cooling off zone.

The wagons R stacked with bricks enter through a door F on the left of the kiln and pass gradually through the kiln to the 35 right so as to deliver burned briquets at G, the doors being air-tight and being opened to admit and deliver one, or two trucks at a time, and the trucks being so arranged to form a continuous platform as is usual. 40 The length of the zones A, B, C, D, and E, is approximately such as to allow of 5, 7, 7, 6, and 3 wagons respectively in each of the said zones. The draft is in the opposite direction to the movement of the trucks 45 and may be obtained either by a high chimney, or preferably by a fan O forcing in air through the flue I, and also under the wagons at the delivery end of the base flue J. In some cases however air may be ad-

mitted to the base flue J, at the chimney 50 and passing up into the kiln at the delivery end and back over the briquets stacked on the wagon platforms.

The kiln is shown arranged to be fired by producer gas which is brought thereto 55 through the flue K, passing into the kiln by the horizontal flues M, and N; these flues are provided with checker work outlets *o*, and *p* respectively, shown in section in Fig. 3, and their size is regulated by dampers *m*, 60 and *n*; further the bridge L is provided on the air heating side of the furnace, and projections *r* and *q*, at each end of the flue base immediately beneath the checker work openings, for the purpose of breaking up 65 the air and gas currents so as to obtain intermixing of the two as much as possible. A smaller amount of gas enters through *p*, than through *o*, its principal object being to heat the air for combustion before it 70 reaches the main firing point at *r*, an excess of air is therefore arranged at *q*, which heated both by the gas from *p*, and its passage over the incandescent briquets reaches 75 *r* at a high temperature and produces there an intense heat with very rapid combustion, and in such a way that owing to the restricted area under the gas flues its velocity will be increased and it will produce a protective air current for some little distance 80 into the combustion chamber, thus keeping any possibly unburned gas away from the briquets until its combustion is complete. This is a point of great moment, and further the zone of intense heat is elongated 85 which is also a great advantage. The air for the furnace is introduced from I through the top flue *i*, and is deflected downward on to the hot briquets by the deflectors S, reaching the preliminary gas supply at *q*, 90 therefore at a considerable temperature and largely over the bridge L. Owing to the restricted space under the gas entry flues the air remains in the enlarged section D a considerable time thus taking up greater 95 heat, forming a storage reservoir for hot air.

The combustion chamber proper extends

from r to c , and having a space above the top of the bricks allows of complete combustion therein without likelihood of nascent, or unburned gases mixing with the briquets.

5. In cases such, for instance, as cement mixture bricks, or when carbonic acid and other gases have to be driven off and the products of combustion cannot harm the bricks, baffle walls such as X are built to force the hot 10 gases through the stacked bricks on the wagons. The section B allows of heating of the incoming bricks without possibility of steam, or other deleterious gases, in the products of combustion harming them since 15 the bricks have already undergone a preliminary heating before reaching this section and will be hot enough therefore to prevent any condensation from the products of combustion; the section B is long enough to 20 take six, or seven, wagons; to prevent any deleterious action on the colder bricks beyond the point g a top flue T there opens and carries the products of combustion to the chimney H , via the down side flue t and 25 the underground flue U .

The preliminary heating referred to is attained by introducing fresh air into the base flue J at the delivery end; this may be done through the down flues e ; this air passing 30 along the whole length of the kiln becomes heated—incidentally also keeping the under-gear of the wagon platforms cool—and passes by the underground flue V , and the side flues v into the kiln at w , over the briquets and out again at the openings u and flues t to the chimney H via flue U . A damper 35 such as W can be introduced between two of the wagon loads at the point g if desired, though being preferably operated on the 40 "plenum," or forced draft principle; the amount of any products of combustion, which may enter the preliminary heating chamber is not enough to be of any consequence.

45. A considerable advantage of the "plenum" system is that only a low chimney stack is required for the purpose of getting rid of the products of combustion; further in the system above set forth since the products of combustion never reach the cold briquets no condensation of steam takes place, the briquets are not harmed thereby, and greater economy of working is secured as no re-evaporation of such condensation needs 50 to take place.

It must be understood that though shown in the drawings as fired by producer gas the kiln may be fired by coal dust, or the like, in which case the flue K would be the flue from 55 a furnace, or fire place attached to the side of the kiln.

I am aware that prior to this invention tunnel kilns have been constructed having

preliminary heating of the incoming goods and also an enlarged combustion chamber. I therefore do not claim such a combination broadly; but

What I do claim as my invention is:

1. The combination, in a tunnel kiln, of a combustion chamber having a main horizontal gas inlet with an enlarged combustion zone, and an auxiliary gas inlet directed toward the air supply for the main gas inlet, substantially as and for the purpose set forth.

2. A tunnel kiln having a combustion chamber of large volume in proportion to the volume occupied by the goods, an air preheating chamber enlarged to the same or a greater extent than the combustion chamber throughout the whole of its length, a section of kiln between the combustion and preheating chambers restricted in cross sectional area nearly to the space occupied by the goods, horizontal gas inlets to the combustion chamber where it joins the restricted section, means for conveying bricks through said combustion chamber and delivering the same at one end of the tunnel, and means for admitting air into said preheating chamber and the restricted section being such that the speed of the draft through the restricted area projects it a considerable distance into the combustion chamber before becoming mixed with the entering gas, and being such that the passage of air through the preheating chamber takes place slowly, substantially as described.

3. In a tunnel kiln, the combination of a combustion chamber having a main horizontal gas inlet, with an enlarged air heating chamber just prior to the combustion chamber, deflectors for directing the air current on to the hot bricks, and an auxiliary gas inlet and baffle walls for further heating the air for combustion, substantially as described herein.

4. The combination, in a tunnel kiln, of a combustion chamber having a main horizontal gas inlet with an enlarged combustion zone, an enlarged air heating zone, means for heating the air therein, a length of tunnel of reduced height between the air heating and combustion chambers, a top flue for removing the products of combustion before reaching the drying zone, a base flue, means for delivering fresh air to the base flue at the delivery end of the kiln, and flues for delivering the air in the base flue to the preliminary drying zone of the kiln, all substantially as and for the purpose set forth.

5. In a tunnel kiln, the combination of a combustion chamber having a main horizontal gas inlet, an enlarged air heating chamber prior to the combustion chamber, de-

reflectors therein, an auxiliary horizontal gas inlet and baffle walls opening into the air heating chamber, a top fresh air supply flue to the air heating chamber, a base flue, a 5 top discharge flue prior to the drying zone, a delivery flue from the base flue to the drying zone, a discharge flue from the latter, and a fan delivering air into the top fresh air supply flue and to the base flue at the

delivery end of the tunnel, all substantially 10 as described herein.

In testimony whereof I affix my signature in presence of two witnesses.
